FRUIT PACKER'S STAND

Edwin R. Walker, Yakima, Wash., assignor to
Food Machinery Corporation, San Jose, Calif.,
a corporation of Delaware

Application March 5, 1932, Serial No. 597,018

17 Claims. (Cl. 226—129)

This invention relates to improvements in fruit packers' stands such as are used in packing houses for the purpose of supporting boxes while they are being packed.

5 When the packer finishes packing a box, it is transferred to a conveyor for delivery to a lidding machine or other destination. Such conveyors are commonly of the gravity type and frequently of the type known as "side wheel" conveyors which, generally speaking, comprise a pair of spaced parallel side rails in each of which is journaled throughout its length a series of small wheels or rollers similar to those used on roller skates. These conveyors are not only cheaper 10 than the well known cross roller type of conveyor, but are better suited for handling packed boxes of fruit, as the free space between the rails accommodates the bulged bottoms of the boxes resulting from tight packing.

20 In order to transfer the boxes from the packing stands to a conveyor of the side wheel type, it has heretofore been necessary to lift the boxes from the stands and carry them to the conveyor. As much of the packing is done by women, the transfer of boxes is taken care of by other attendants 25 employed for the purpose.

It is the principal object of this invention to provide a packing stand of such character that boxes may be transferred therefrom to a conveyor without the necessity of lifting or carrying them from the stand.

A further object is to construct such a stand so that it may be operated expeditiously and by the exercise of a minimum of physical effort.

35 Various other objects and advantages will become apparent as the description proceeds in connection with the accompanying drawings which illustrate one embodiment of the invention.

In the drawings:

40 Figure 1 is a side view of the apparatus illustrating the various parts disposed in normal or idle position.

Figure 2 is a view similar to Figure 1 but illustrating the parts in a different position as assumed 45 during the course of operation.

Figure 3 is another view similar to Figure 1 but illustrating the positions assumed by the parts as a box is being deposited upon a conveyor.

Figure 4 is a plan view of the apparatus with 50 portions broken away to better illustrate certain features of construction.

The packing stand illustrated comprises an adjustable frame made up of upper and lower sections so that the upper section may be raised or 55 lowered to suit the convenience of the individual

packer. The lower section comprises the four corner posts 1, secured together by cross braces 2, and may be provided with casters 3 so that the stand may be readily moved about. The upper section of the frame is made up of a pair of bent 5 arms 4 interconnected at their upper ends by a spacer rod 5 and having vertical portions 6 which are releasably clamped to the front corner posts 1 by clamps 7. By loosening the clamps, the upper section of the frame may be adjusted to various 10 elevations as desired.

The usual paper tray is indicated at 8 and is supported by an arm 9 having a bearing 10 slidably mounted upon the vertical standard 11. An adjustable collar 12 serves to regulate the elevation 15 of the tray.

A box supporting pan or platform 13, provided at its lower edge with a handle 14, overlies the frame and is interconnected therewith at each side by means of a pair of links 15 and 16, pivoted together at 17. The links 15 are interconnected at their outer ends by a rod 18 which passes through side flanges of the platform, while the links 16 are pivoted to a rod 19 extending between the frame members 4. The normal position of 25 the platform during the packing operation is determined by the lugs 20, which project outwardly from the frame members 4 and engage with notches 21 cut in the links 15. When so engaged the platform is firmly held in place. 30

The upper portion of the platform 13 is supported by a fulcrum including a pair of anti-friction rollers 22 journaled for rotation upon a cross rod 23 extending crosswise between a pair of supporting arms 24, and these arms are 35 mounted to oscillate about the rod 19. Pivoted to the arms 24 and extending downwardly therefrom are connecting rods 25 which are pinned at their lower ends to the arms 26 of a V-shaped foot pedal 27. The ends of the foot pedal arms 40 are pivoted to the lower cross braces 2 at 28. A spring 29 secured at its lower end to one of the cross braces 2 and at its upper end to the rod 23 serves to hold the fulcrum rollers 22 normally in their lowermost position. 45

In the operation of that part of the packing stand thus far described, it will be apparent that a box 30, resting upon the platform 13, may be transferred to an adjacent conveyor such as indicated at 31 by depressing the foot pedal 27 to 50 elevate the fulcrum rollers 22 and then grasping the handle 14 and lifting the lower portion of the platform upwardly about the fulcrum rollers and shifting it rearwardly to overlie the conveyor. The length of the box is such that it extends out- 55

wardly beyond the outer edge of the platform so that when the foot pedal 27 is released the spring 29 lowers the fulcrum rollers, thereby tilting the platform downwardly until the outer end of the 5 box rests upon the conveyor and the platform is supported by the spacer rod 5 which acts as a secondary fulcrum. This position of the parts is illustrated in Figure 3.

By reason of the frictional contact between the 10 conveyor and that portion of the box resting thereon, the operator may now withdraw the platform from beneath the box without carrying the box with it, and the box is released upon the conveyor whereupon it moves by gravity to 15 its destination. The platform is then lowered into its original position and is ready to receive another box.

In order to minimize the effort required to 20 lift the lower portion of the platform when a loaded box is resting thereon, I provide a mechanism actuated by the foot pedal 27 for shifting the box upwardly along the platform to shift its weight closer to the fulcrum point. This mechanism comprises a pusher finger 32 in the form 25 of a heavy wire or rod, doubled upon itself to form a pair of supporting legs 33 which, at their lower ends, are spread apart to be pivotally secured to the lower cross braces 2. The finger 32 projects upwardly through a slot 34 in the platform 30 13 and is guided and actuated by a yoke 35 passing loosely around the finger and secured to a spacer rod 36 extending between the arms 24.

In operation, the parts are normally disposed 35 in the positions illustrated in Figure 1, and when 35 the operator has packed the box 30 and wishes to transfer it to the conveyor the foot pedal 27 is depressed, thereby elevating the fulcrum rollers 22 and simultaneously the movement of the rod 36 carried by the arms 24 shifts the finger 40 32 forwardly to push the box upwardly along the platform nearer the fulcrum point, as seen in Figure 2. When the box is thus shifted, it becomes an easy matter to lift the platform about the fulcrum rollers 22 by means of the handle 14, 45 whereupon the platform is shifted rearwardly to bring the box over the conveyor. The pedal is then released to lower the fulcrum rollers, thus tilting the platform away from the packing stand and dropping the outer end of the box upon the 50 conveyor. The platform is thereupon withdrawn, leaving the box on the conveyor, and is dropped back into its original position, ready to receive another box to be packed.

It will be appreciated that although for the 55 sake of this disclosure I have illustrated and described the operation of the invention in connection with its use in packing fruit boxes and transferring the same to side wheel conveyors, its use is not limited thereto, but it may be used for packing other types of containers with articles other than fruit, and it may be used to transfer such containers to other types of conveyors.

Having now described my invention and in 60 what manner the same may be used, what I claim as new and desire to protect by Letters Patent is:

1. In a box supporting stand, a frame including a fulcrum, a movable box supporting platform supported by said frame and resting upon said fulcrum, said platform being tiltable about said fulcrum and shiftable thereacross and means interconnecting the platform and frame for limiting movement of the platform, said means being extensible whereby the platform may be shifted 70 crosswise of the frame across the fulcrum and 75

tilted thereabout to overhang the frame and tilt downwardly away therefrom.

2. In a box supporting stand, a frame including a fulcrum, a movable box supporting platform supported by said frame and resting upon said fulcrum, said platform being tiltable about said fulcrum and shiftable thereacross, and a flexible linked connection between the platform and frame whereby the platform may be shifted crosswise of the frame across the fulcrum and 10 tilted thereabout to overhang the frame and tilt downwardly away therefrom.

3. In a box supporting stand, a frame including a fulcrum, a movable box supporting platform supported by said frame and resting upon said 15 fulcrum, and means interconnecting the platform and frame comprising a link pivotally secured at one end to the frame, and a second link pivotally secured at one end to the platform, the opposite ends of said links being pivoted together 20 whereby the platform may be shifted outwardly across the fulcrum to overhang the frame and may be tilted about the fulcrum to tilt downwardly away from the frame.

4. A box supporting stand comprising a frame, 25 a platform supported thereupon, means interconnecting said platform and frame comprising a pair of connecting links pivotally interconnected at adjacent ends and pivotally secured at their opposite ends to the platform and frame 30 respectively, and a lug projecting from the frame, one of said links being provided with means for engaging said lug to hold the platform in place.

5. A box supporting stand comprising a frame, 35 a platform supported thereupon at an incline toward the front of the frame, a fulcrum supporting the upper portion of the platform, and extensible means interconnecting the lower portion of the platform with the frame whereby the 40 platform may be shifted rearwardly of the frame and tilted downwardly about the fulcrum away from the frame.

6. A box supporting stand comprising a frame, 45 a platform supported upon said frame for shifting and tilting movement relative thereto, extensible means interconnecting the platform and frame whereby the platform may be shifted outwardly to overhang the frame and tilt downwardly away from the frame, and means for vary- 50 ing the angle of tilt.

7. A box supporting stand comprising a frame, 55 a platform supported thereupon, a fulcrum supporting the rear portion of the platform, extensible means interconnecting the platform and frame whereby the platform may be shifted outwardly therefrom across the fulcrum, and means for elevating and lowering the fulcrum with respect to the frame to vary the elevation of the 60 outer end of the platform.

8. A box supporting stand comprising a frame, 65 a platform supported thereupon at an incline toward the front of the frame, a movable fulcrum supporting the upper portion of the platform, extensible means interconnecting the lower portion of the platform with the frame whereby the platform may be lifted about the fulcrum and shifted rearwardly to overhang the frame, means for elevating said fulcrum to vary the elevation of the overhanging edge of the platform, 70 a stationary fulcrum, and means for lowering the movable fulcrum to lower the platform onto the stationary fulcrum and tilt it away from the frame.

9. A box supporting stand comprising a frame, 75

5 a platform supported thereupon at an incline toward the front of the frame and provided with a slot therethrough, a fulcrum supporting the upper portion of the platform, a finger projecting upwardly through the slot to engage the lower end of a box resting upon the platform, means for moving said finger to push the box upwardly along the platform, and flexible means interconnecting the platform with the frame 10 whereby the platform may be lifted upwardly about the fulcrum and shifted rearwardly across the fulcrum to overhang the frame.

10. A box supporting stand comprising a frame, a platform supported thereupon at an incline toward the front of the frame and provided with a slot therethrough, a movable fulcrum supporting the upper portion of the platform, a finger projecting upwardly through said slot to engage the lower end of a box resting upon the platform, 15 means for simultaneously elevating said fulcrum and moving the finger to push the box upwardly along the platform, flexible means interconnecting the platform with the frame whereby the platform may be lifted upwardly about the fulcrum and shifted rearwardly across the fulcrum to overhang the frame, and means for lowering the fulcrum to tilt the overhanging platform away from the frame.

11. In a box supporting stand, a frame including a fulcrum, a movable box supporting platform supported by said frame in a normally downwardly inclined position toward the front of the frame and resting upon said fulcrum, said platform being pivotable about said fulcrum and 25 shiftable rearwardly thereacross to overhang the frame and tilt downwardly away therefrom, and means interconnecting the platform and frame to limit movement of the platform.

12. In a box supporting stand, a frame including a fulcrum, a movable box supporting platform supported by said frame in a normally downwardly inclined position toward the front of the frame and resting upon said fulcrum, said platform being pivotable about said fulcrum and shiftable thereacross, and means interconnecting the platform and frame to allow for lifting of the platform about the fulcrum and for shifting movement rearwardly across the fulcrum where-

by the platform may overhang the frame and tilt downwardly away therefrom.

13. A box supporting stand comprising a frame, a platform supported thereby in a normally inclined position, a fulcrum for the upper portion of the platform, said platform being pivotable about said fulcrum and shiftable thereacross to overhang the frame, and means for varying the elevation of the fulcrum with respect to the frame.

14. A box supporting stand comprising a frame, a platform supported thereby in normally inclined position, a fulcrum supporting the upper portion of the platform, said platform being tiltable about said fulcrum and shiftable thereacross, 15 and means associated with the platform for actuation by an operator to lift the platform about the fulcrum and shift it thereacross to overhang the frame.

15. A box supporting stand comprising a frame, 20 a platform supported thereby in a normally inclined position, a fulcrum for the upper portion of the platform, said platform being pivotable about said fulcrum and shiftable thereacross, a pusher member disposed to engage a box resting 25 upon the platform, and means for actuating said pusher member to push the box upwardly along the platform.

16. A box supporting stand comprising a frame, a platform supported thereby in a normally inclined position, a fulcrum supporting the upper portion of the platform, a pusher member disposed to engage a box resting upon the platform, means for actuating said pusher member to push the box upwardly along the platform, and means 30 35 interconnecting the platform and frame in a manner to allow for lifting of the platform about the fulcrum, and shifting movement across the fulcrum whereby the platform may overhang the frame.

17. A box supporting stand comprising a frame, a platform carried thereby in a normally inclined position, a pivotal support for the upper portion of the platform, about which the platform may be lifted, a pusher member disposed to 40 45 engage a box resting upon the platform, and means for actuating said pusher member to push the box upwardly along the platform.

EDWIN R. WALKER.
